APPARATUS FOR INTRODUCING MELTS
INTO CASTING MOLDSJens Aalbørg Rønn, Skive, Denmark, assignor to
W. Hellesen and Co., Copenhagen, DenmarkApplication November 21, 1935, Serial No. 50,962
In Germany November 22, 1934

8 Claims. (Cl. 22—57.1)

This invention relates to improvements in apparatus for introducing melts into casting molds, especially for dental purposes and has for its main object to provide for a simple and cheap apparatus, which enables the instantaneous production of a high vacuum. A further object is to provide for an apparatus in which the vacuum is maintained for a sufficiently long time. Still another object is to provide for an apparatus enabling the production of a high vacuum also after long use of the apparatus.

It is known to make dental and other castings under reduced pressure, the object of the reduced pressure being the production of castings free or nearly free from gas bubbles. The known apparatus for this purpose consists essentially in a suction apparatus fitted with a piston, on which the casting mold sits. When the piston is drawn out the melt which lies on the casting mold is sucked into the mold.

These known apparatus do not fulfil the demands made upon them, especially when it is a matter of producing objects with especially thin walls such as plates for the roof of the mouth. The vacuum produced by the piston is not sufficiently great to produce in every case bubble-free castings which exactly reproduce the model. The piston cannot even with the greatest care be made to slide exactly in the cylinder so that the requisite high vacuum is produced and maintained sufficiently long. The apparatus loses its tight fit with increasing use and its life is in consequence short.

The apparatus according to the present invention obviates all these disadvantages. It consists essentially of two hollow cylinders open at one end which slide one within the other, one of which can be made to move in respect to the other by means of the action of a spring for example, and one of which is connected to the casting mold. The hollow space inside the two cylinders contains a liquid filling, in particular oil.

One embodiment of the invention is illustrated in section in the drawing.

The mold support 1 in which the mold is formed in the usual way by means of a wax model and porous embedding material, has a projecting part 2 with a conical interior which fits a cone 3 in the head 4 of the inner hollow cylinder 5, which is open at the base. A channel 6 formed round the cone 3 in the head 4 serves to hold oil or the like which acts as a caulking medium. In this channel 6 there is also a ring 7 with a handle 8, which serves to lift off the mold support 1 after the casting has been completed. Two handles 9 are further provided in the head for setting the appara-

tus under tension. The head 4 also carries a protecting tube 10, to which a worktable 11 is fixed. The hollow cylinder 5 is inserted into a hollow cylinder 12 open at the top, the base 13 of which is screwed into the foot 14 of the apparatus. A spring 15 is positioned in the hollow space and formed by the cylinders 5 and 12 and filled with oil or other liquid. This spring is put under tension when the cylinder 5 is moved downwards and is maintained in this position by a foot-pedal lever 18 which oscillates about a pin 17 and is held by a spring 16, and which grips over a ring shaped shoulder 19 which is fixed to the protecting tube 10 which is joined to the head 4. The lower part 20 of the shoulder 19 works in connection with a shoulder 21 on the outer surface of the cylinder 12.

The modus operandi of the apparatus is as follows:

The two hollow cylinders 5 and 12 are pushed together by means of the handles 9, so that the spring 15 is put under tension. The lever 18 catches over the shoulder 19 so that the spring 16 remains in position. The mold support 1, which carries the mold previously prepared by means of a wax model and porous embedding material, is fitted over the cone 3 of the apparatus for producing the vacuum, oil or another liquid being run into the channel 6. Molten metal is introduced into a trough in the upper surface of the mold. The connection between the cylinders 5 and 12 is broken by applying pressure on the lever 18. The spring 15 is released and presses the cylinder 5 upwards in the cylinder 12 until the shoulder 20 abuts against the shoulder 21. A vacuum is therefore produced in the mold so that the metal is sucked into the mold. When the casting is cold, the mold support 1 and the mold and casting are freed from the cone 3 by turning the ring 7 by means of the handle 8.

The invention is not restricted to the example herein described. For example the inner spring can be replaced by an outer spring. The drawing apart of the two cylinders can be achieved without a spring by means of a weight which is attached to the outer cylinder and when released by a catch moves downwards while the inner cylinder remains stationary, for example is fixed with the aid of the protecting tube to the wall or a work-bench. In this case therefore the outer cylinder which is open at the top is movable and not the inner cylinder which is open at the bottom as is the case shown in the drawing. Likewise both cylinders can be placed horizontally instead of vertically. The connection between the mold support and the vacuum producing apparatus can

also be arranged differently, for example by means of a tube or hose in which case the mold support can stand on the work-bench.

The apparatus described is applicable not only for dental purposes. It can also be used for casting jewelry, machine parts and the like. It can be applied for making castings of metals or other castable materials generally.

I claim:

10. 1. An appliance for use in making castings comprising two vertical hollow cylinders open at opposite ends, one of said cylinders sliding within the other cylinder, a column of liquid in the hollow space formed by said two cylinders, means for connecting the upper part of said hollow space formed by said cylinders with a casting mold and a spring moving one of said cylinders relative to the other cylinder.
15. 2. Appliance for use in making castings comprising a hollow cylinder open at the top, a foot connected with the bottom of said hollow cylinder, another hollow cylinder open at the bottom slidably fitted in said first hollow cylinder, means for connecting the upper part of the hollow space formed by said cylinders with a mold arranged on the top cover of said second cylinder, a column of liquid in said hollow space, a spring arranged in said hollow space and releasable means for maintaining both cylinders in telescoped conditions
20. 30. with said spring under tension.
25. 3. An appliance for use in making castings comprising a hollow cylinder open at the top, a foot connected with the bottom of said cylinder, another hollow cylinder open at the bottom slidably fitted in said first hollow cylinder, a protecting tube connected with said second inner cylinder and surrounding said first outer cylinder, means for connecting the upper part of the hollow space formed by said cylinders with a mold arranged on the top cover of said second cylinder, a column of liquid in said hollow space, a spring arranged in said hollow space and releasable means for maintaining both cylinders in telescoped condition with said spring under tension.
35. 45. 4. An appliance for use in making castings comprising a hollow cylinder open at the top, a foot connected with the bottom of said hollow cylinder, another hollow cylinder open at the bottom slidably fitted in said first hollow cylinder, a protecting tube connected with said inner cylinder and surrounding said outer cylinder, handles connected with said inner cylinder, means for connecting the upper part of said hollow space formed by said cylinders with a mold arranged on the top cover of said second cylinder, a column of liquid in said hollow space, a spring arranged in said hollow space, and releasable means for maintaining both cylinders in telescoped condition with said spring under tension.
50. 55. 5. An appliance for use in making castings comprising a hollow cylinder open at the top, a foot connected with the bottom of said hollow cylinder, another hollow cylinder open at the bottom slidably fitted in said first hollow cylinder, a protecting tube connected with said inner cylinder and surrounding said outer cylinder, handles connected with said inner cylinder, a shoulder at the end of said protecting tube, a foot-pedal lever on said foot cooperating with said shoulder

adapted to lock said cylinders in telescoped position, means for connecting the hollow space formed by said cylinders with a casting mold, a column of liquid in said upper part of the hollow space and a spiral spring arranged in said hollow space.

6. An appliance for use in making castings comprising a hollow cylinder open at the top, a foot connected with the bottom of said hollow cylinder, another hollow cylinder open at the bottom slidably fitted in said first hollow cylinder, a protecting tube connected with said inner cylinder and surrounding said outer cylinder, handles connected with said inner cylinder, a shoulder at the lower end of said protecting tube, a foot-pedal lever on said foot cooperating with said shoulder adapted to lock said cylinders in telescoped position, a conical mold carrier in the cover of said inner cylinder, a longitudinal bore in said carrier in correspondence with the bore in said cover leading to the hollow space formed by said cylinders, a column of liquid in said hollow space and a spiral spring arranged in said hollow space.

7. An appliance for use in making castings comprising a hollow cylinder open at the top, a foot connected with the bottom of said hollow cylinder, another hollow cylinder open at the bottom slidably fitted in said first hollow cylinder, a protecting tube connected with said inner cylinder and surrounding said outer cylinder, handles connected with said inner cylinder, a shoulder at the end of said protecting tube, a foot-pedal lever on said foot cooperating with said shoulder adapted to lock said cylinders in telescoped position, a conical mold carrier in the cover of said inner cylinder, a longitudinal bore in said carrier in correspondence with a bore in said cover leading to the hollow space formed by said cylinders, a channel in said cover surrounding said conical carrier, a column of liquid in said hollow space and a spiral spring arranged in said hollow space.

8. An upright casting apparatus comprising a base, an outer hollow cylinder permanently secured thereto and an open-ended slideable cylinder mounted within said outer cylinder, a head for the upper end of the slideable cylinder provided with an axial aperture therethrough and an annular upwardly opening channel adapted to contain a caulking substance, a compression spring acting between said base and said head in the cylinder space, a cylindrical jacket secured in said head and forming an enclosure around said outer cylinder, a shoulder at the bottom end of said jacket, a treadle pivotally mounted on the base and adapted to engage said shoulder in order to retain the jacket in the slideable cylinder in the lowered position, stops on said outer cylinder adapted to cooperate with said shoulder to limit the upward movement of said jacket and slideable cylinder, a ring fitted in said channel and a mold support having a shank engaging in said channel in said head, means for locking the ring to said head, other means on said head for manually lowering the head with the jacket and slideable cylinder in order to compress the spring and a liquid column filling the space within said slideable cylinder.
